FOLDING TABLE

Dewey S. Lewis, Louisville, Ky., assignor to Adler Manufacturing Co., Incorporated, Louisville, Ky., a corporation of Kentucky

Application May 3, 1935, Serial No. 19,541

7 Claims. (Cl. 311—99)

My invention relates to tables equipped with mechanisms organized to provide a pivot and locking means for each individual supporting leg, whereby the latter can be folded for the closed position or extended in terms of the top for the open position and then secured in either of the selected positions.

The primary object of the invention is to provide sturdy hinges of simple structure for the legs of tables known in the furniture industry as "folding" or card tables.

An important object of the invention is the embodiment of principles, structure and materials to enable the uninitiated user to readily understand the operations incident to extending the legs or opening the table for use, also for folding or closing the legs for storage.

A still further object of the invention contemplates an organization of metal and wood parts having superior enduring mechanical properties, the component parts of which can be readily produced expeditiously, assembled and finished to constitute the final product.

With the foregoing and other objects, which will be revealed as the description of the details of the construction proceeds and hereinafter claimed, it must be understood that changes from the selected embodiment of my invention can be indulged without departing from the scope of my invention.

Drawing

Figure 1 is a fragmentary elevational view of the upper section of a table leg attached to a portion of a top to illustrate the former in full lines in extended or open position, the dotted lines indicating the folded or closed position.

Fig. 2 is a similar view taken at right angles in the direction of the arrow 2.

Fig. 3 illustrates the plan view of the blank of the yoke member prior to final forming in which stage it is shown in Fig. 4.

Fig. 5 indicates the developed surface in plan view of the latch arm prior to forming in which state it is shown in Fig. 6.

Fig. 7 is an elevational view of Fig. 1 in modified form, shown partially in cross section.

Structure

Numeral 10 indicates the top portion of a leg of a folding table in extended position. 11 is a yoke secured by screws 14 to flange 12 which with the top slab 13 is to be regarded herein as the table top. The leg is pivotally mounted on the

shaft 15 which is suitably secured in holes, preferably riveted.

Coincident with the blanking operation for producing part 11 as shown in Fig. 3, tongue 111 is also cut as indicated. A subsequent operation 5 shapes the blank into the yoke as illustrated in Fig. 4 with the tongue 111 having been orientated through 180°, and the inner faces 112 of arms 110 forced into parallel relation to receive the parallel faces of leg 10, said faces 110 being correlated to contribute to a desired free but firm swinging action. Hole 116 in tongue 111 is provided to receive a screw 14 while ear 115 received another screw 14. For assembly, the leg is first equipped with the hardware, dealt with herein, 15 when it is transferred to the table top and secured in working relation thereto by screws 14.

Numerals 16 represents a sleeve driven into the leg and has slidably mounted therein a hollow plunger 17 in which is disposed compression 20 spring 18, the bottom end of which is fixed into the reduced portion 19 of the sleeve. The arms 200 of 20 are pivoted onto the leg by shaft 21 which is located in fixed spaced parallel relation to shaft 15 to effect a definite operating relation 25 between the yoke and latch arm. The plunger and spring are provided and located to normally press surface 203 or arcuate lobe 204 of the latch arm against the cam or track 114 or arcuate notches 117 of yoke 11.

In Figs. 1 and 5 lobe 204 is eccentric to axis 201 of shaft 21 to produce a wedging action with notch 117 (Fig. 1) which is concentric to said axis. A similar wedging action can be effected by reversing the relation of these faces, i. e. notch 35 117 is made eccentric and lobe 204 concentric to axis 201 as shown in Fig. 7. In each case the travel of the locking lever is stopped by the wedging action without any lost motion.

The wedging action based on the principle of 40 the eccentric relation of the cam faces, described in the preceding paragraph, results in a secure lock, not only at the outset of the assembly, but throughout the life of the table equipped with same. These principles contribute 45 to the production of a highly satisfactory table and the hardware at a very low cost.

Faces of notches 117 and cams 204, and the bearings for shafts 15 and 21 being of stamped 50 steel are not formed with true surfaces or even consistent irregular ones, all of which is recognized by producers of stamped sheet metal. When first assembled spring 18 forces cam surfaces, i. e., one or both of same, into engagement with arcuate notches 117, usually for a single 55

point contact. Repeated operations as in normal usage, develops the contacts into a long line bearing for one or both cams and then into enduring surface contacts for both sets of cam locks. While 5 the irregular areas and burred edges of the bearings are wearing to more durable surfaces the eccentric relations of the faces of the cams and notches compensate for all the wear as well as irregularities and thereby prevent a loose and 10 rickety condition from developing.

Operation

To open the table when legs 10 are lodged in closed position as indicated by the dotted position in Fig. 1, each leg is drawn outwardly, rotating substantially 90° on shaft 15 until it reaches the full line position where a portion of lobe 204 is forced into notch 117 by spring 18 and plunger 17. At this position the leg is firmly secured, 20 the wedging action referred to hereinbefore having been organized to prevent any lost motion or looseness and to compensate for wear of the main bearing and the elements constituting the latch. Pressure exerted on latch 20 by the 25 human hand releases the lock when the leg can be readily returned to the dotted or closed position. As this pressure is released the spring forces the lever back against cam or track 114, or returns the cam faces 204 to engagement with 30 notches 117, which in turn forces the back side of leg 10 (as viewed from Fig. 2) against the yoke 11 and effects the wedging action mentioned heretofore.

I claim:

- 35 1. A folding table comprising a top and a leg swingably connected thereto by a pivot mounted in a yoke secured to the top, said yoke having a pair of arms which embrace correlated faces of the leg, the edge of each arm being fashioned 40 with a cam face terminating in a concave notch, a spring pressed locking lever pivoted to the leg and equipped with a pair of convex cam faces which cooperate with said notches to secure the leg in the extended position, the free end of said 45 lever being pressed outwardly by a spring lodged in said leg.
2. A folding table comprising a top and a leg swingably connected thereto by a pivot mounted in a yoke secured to the top, said yoke having 50 a pair of arms which embrace correlated faces of the leg, the edge of each arm being fashioned with a cam face substantially concentric to said pivot and terminating in a concave notch, a spring pressed locking lever pivoted to the leg 55 and equipped with a pair of individual cam faces concentric to the pivot of the locking lever and each of said faces cooperating with its related notch to secure the leg in the extended position.
- 60 3. A folding table comprising a top and a leg swingably connected thereto by a pivot mounted in a yoke secured to the top, said yoke having a

pair of arms formed with substantially parallel faces which embrace correlated faces of the leg, the edge of each arm being fashioned with a cam face substantially concentric to said pivot and terminating in an arcuate notch, a spring 5 pressed locking lever pivoted to, also embracing the leg and equipped with arcuate cam faces concentric to the pivot of the locking lever and organized to cooperate with said notches to secure the leg in the extended position, said notches 10 being eccentric to the pivot of the locking lever.

4. A folding table comprising a top and a leg swingably connected thereto by a pivot mounted in a yoke secured to the top, said yoke having a pair of arms which embrace correlated faces 15 of the leg, the edge of each arm being fashioned with a cam face and terminating in a concave notch, a spring pressed locking lever pivoted to, also embracing the leg and equipped with cam faces eccentric to the pivot of the locking lever 20 which mesh with said notches to secure the leg in the extended position, said notches being concentric to said pivot to effect a wedging action between said faces and the notches.

5. A folding table comprising a top and a leg 25 swingably connected thereto by a pivot mounted in a yoke secured to the top, said yoke having a pair of arms formed with substantially parallel faces which embrace correlated faces of the leg, the edge of each arm being fashioned with a cam 30 face concentric to said pivot and terminating in an arcuate notch, a spring pressed locking lever pivoted to the leg and equipped with arcuate cam faces eccentric to the pivot of the locking lever 35 and organized to cooperate with said notches to secure the leg in the extended position.

6. A folding table comprising a top and a leg swingably connected thereto by a shaft mounted in a yoke secured to the top, said yoke having 40 a pair of arms which embrace correlated faces of the leg, a spring pressed locking lever pivoted to the leg and having concentric arcuate cam faces formed in the edge of same, the edge of each arm of said yoke being formed with a cam 45 which terminates in a deep notch to receive the faces of said lever and form a stop for the latter and thereby secure the leg in the extended position.

7. A folding table comprising a top and a leg 50 swingably connected thereto by a shaft mounted in a yoke secured to the top, said yoke having a pair of arms which embrace correlated faces of the leg, a spring pressed locking lever pivoted to the leg and equipped with arcuate cam faces, 55 the edge of each arm of said yoke being formed with a cam which terminates in a deep arcuate notch to receive only a portion of the faces of said lever and thereby effect a wedging action when in the extended position.

60 DEWEY S. LEWIS.
